US00D940500S

(12) **United States Design Patent** (10) **Patent No.:** **US D940,500 S**
Bannister et al. (45) **Date of Patent:** **** Jan. 11, 2022**

(54) **LID**

(71) Applicant: **SHARKNINJA OPERATING LLC**,
Needham, MA (US)

(72) Inventors: **Sam William Bannister**, Leybourne
(GB); **Michael Sloban, Jr.**, Cambridge,
MA (US)

(73) Assignee: **SHARKNINJA OPERATING LLC**,
Needham, MA (US)

(**) Term: **15 Years**

(21) Appl. No.: **29/694,052**

(22) Filed: **Jun. 6, 2019**

(51) LOC (13) Cl. **31-00**

(52) U.S. Cl.

USPC **D7/391**; D7/376; D7/378

(58) **Field of Classification Search**

(57) **CLAIM**

The ornamental design for a lid, as shown and described.

DESCRIPTION

FIG. 1 is a perspective view of a lid, showing our new design;

FIG. 2 is a top view of the embodiment shown in FIG. 1;
FIG. 3 is a bottom view of the embodiment shown in FIG. 1;

FIG. 4 is a side view of the embodiment shown in FIG. 1;
FIG. 5 is another side view of the embodiment shown in FIG. 1;

FIG. 6 is a front view of the embodiment shown in FIG. 1;
and,

FIG. 7 is a rear view of the embodiment shown in FIG. 1.

1 Claim, 5 Drawing Sheets

US D940,500 S
